UNITED STATES PATENT OFFICE.

ANDREW T. HALL, OF NEWPORT, RHODE ISLAND, ASSIGNOR TO THE GOVERNMENT
OF THE UNITED STATES.

TORPEDO.

Application filed August 12, 1920. Serial No. 403,050.

To all whom it may concern:

Be it known that I, ANDREW T. HALL, a citizen of the United States, residing at Newport, Rhode Island, have invented new and useful Improvements in Torpedoes, of which the following is a specification.

This invention relates to improvements in torpedoes and more particularly to what is known as the water spray associated with the combustion flask of the torpedo.

As is well-known to those skilled in the art, the torpedo is driven by what might be termed the products of combustion formed by the admission to the combustion flask of alcohol which is ignited, compressed air, and water which is converted into steam. This mixture of gases passes from the combustion flask to the turbine all in a well-known manner.

20 The present invention is designed to eliminate the necessity of a check valve in the water spray and comprises a simple and practical construction which may be easily and inexpensively manufactured and assembled as well as installed in combustion flasks now in general use without material alteration.

25 A further object is to provide a water spray which will be more reliable and efficient in use and operation and adapted to insure the firing of a successful hot shot by eliminating the heretofore danger of extinguishing the alcohol flame by too early an admission of the water to the combustion flask.

30 Other objects will be in part obvious and in part hereinafter pointed out in connection with the accompanying drawing wherein is illustrated one of various possible embodiments of the present invention.

35 Figure 1 is a vertical, longitudinal, sectional view showing part of the combustion flask and the water spray associated therewith.

40 Figure 2 is a cross sectional view taken on substantially the line 2/2, Figure 1.

45 Figure 3 is an enlarged detail view showing the lower part of the spray in open position.

50 Referring now to the drawings in detail, 6 denotes the upper part of the combustion flask of standard construction provided with an opening 8 through which the water spray member 10 is adapted to pass and in

which it is secured. This water spray member comprises broadly the tubular member 11, the upper part of which is provided with a lateral passage 12 communicating with passage 13 to a pipe coupling 14, the water being admitted through pipe 15 from the main supply tank. The member 14 is of peculiar shape adapted to surround the body member of the spray and be held in locked position thereby when the parts are assembled.

The present invention resides more specifically in the lower part of the spray. A main spray member 16 is threaded in to the end of the tubular member 10 and is provided with a dependent portion 17 slotted at 18 through which a pin or key 20 passes to hold a closing member 21 in the position shown in Figure 1. The member 16 as shown more clearly in Figure 2 is provided with a plurality of inlet openings 22 extending substantially parallel with the axes and terminating at the lower ends with a lateral bore 23 communicating with a chamber 24 closed by means of plugs 25. The lower part of this chamber is provided with a lateral outlet 26 normally closed by the closure member 21 which is held in its closed position by means of a fusible sleeve 27. This fusible member 27 is held in place by means of a screw plug 28 which also engages the lower end of the dependent portion 17 and is held in place by means of pin 30 after the parts are assembled.

The operation of this device is substantially as follows:—

When the torpedo is fired the piston ignites the alcohol burner not shown and the heat within the combustion flask quickly melts the fusible member 27 whereupon the water pressure entering from pipe 15 through tubular member 10, passages 22 and 23 to chamber 24 and outlet 26 urges the closing member 21 downwardly as permitted by the pin and slot connections after which the water is sprayed into the combustion flask and converted into steam by action of the alcohol burner.

It is believed that the construction and operation of the device herein shown will be apparent to those skilled in the art and that various modifications will suggest themselves and it is, therefore, intended that

the accompanying claims shall be construed as broadly as possible in view of the art to cover such modifications.

The invention is of simple and practical construction, reliable and efficient in use and operation and is particularly adaptable for eliminating the possibilities of cold shots by the premature admission of water to the combustion flask.

10. What I claim is:—

1. In combination with a combustion flask of a torpedo, a water spray in said flask, comprising a tubular member having an outlet, and means closing said outlet adapted to be released on material increase of temperature within the flask, said means including a fusible holding member.

2. In combination with the combustion flask of a torpedo, a water spray therein comprising a tubular member connected with the source of water supply, a spray member at one end of said tubular member and fusible means normally holding the outlet to said spray member in closed condition.

3. In combination with the combustion flask of a torpedo, a water spray therein comprising a tubular member connected with the source of water supply, a spray member at one end of said tubular member, means normally closing the outlet to said spray member and fusible means associated with said closing means adapted to release the closing means on material increase in temperature.

4. In a water spray within the combustion flask of torpedoes, in combination, a tubular member adapted to be connected with a source of fluid, said tubular member having outlet openings at its opposite end and means including a fusible holding member normally closing said outlet openings.

5. In a spray device within the combustion flask of a torpedo, in combination, a tubular member connected with a source of fluid supply and outlet openings near one

end, a member normally closing said outlet openings and fusible means holding said member in closing position and adapted to release the same on material increase of temperature in the combustion flask.

6. In combination with a torpedo flask, a spray device therein comprising a tubular member adapted to be connected with a source of fluid pressure, a spray member near one end thereof, including a plurality of outlet openings, a member normally closing said outlet openings and having a sliding connection with the spray member and a fusible member normally holding said closing member in closing position and adapted to release the same when the temperature in the combustion flask is materially increased.

7. In combination with the combustion flask of a torpedo, a spray device therein comprising a tubular body member, a spray having a plurality of openings associated with one end thereof, a member normally closing said openings and having a sliding connection with said spray member, a fusible sleeve holding said closing member in normally closing position and means securing said fusible sleeve in position whereby when said fusible sleeve melts, the closing member drops away from said spray openings.

8. A spray device within the combustion flask of a torpedo comprising a tubular member connected with a suitable source of fluid pressure in a spray head having a plurality of longitudinal openings connected with laterally extending outlet openings, a sleeve member normally closing said openings having a sliding connection with the spray head and a fusible sleeve holding said closing member in position and adapted to release said closing means when the temperature in said flask is materially increased.

Signed at Newport, Rhode Island, this 13 day of March, 1920.

ANDREW T. HALL.
